UNITED STATES PATENT OFFICE

PRESTON D. CALLUM, OF BALTIMORE, MARYLAND

KNIFE GUARD

Application filed September 9, 1925. Serial No. 55,212.

This invention relates to guards and particularly to guards adapted for attachment to knife handles.

Heretofore, in the meat packing industry 5 little or no attention has been paid to the protection of employees in the various operations of butchering and cutting of meat, against injury to the operating hand caused by the hand slipping from the handle to the 10 blade.

When operating with a knife equipped with an ordinary handle, an operator frequently receives very serious injury to the operating hand due to the hand coming in 15 contact with the blade. The slipping of the hand is frequently caused by an accumulation of fatty substances and etc. on the handle or the hand. Such slipping is also caused by the fatigue of the hand and wrist brought 20 on by the constant gripping of the handle.

An object of my invention is to provide a 25 knife guard which will overcome the objections to the knives now in general use by the production of a guard which will amply protect the operating hand in any and all of the various operations of the meat packing industry.

Another object of my invention is to provide a knife guard designed for attachment 30 to any of the various types of knives now in general use, a guard which may be easily and quickly attached and removed in case of a broken or worn out blade.

A further object of my invention is to provide a guard which is positive, highly efficient in operation and of marked simplicity, being formed of one piece stamped or punched in such form or forms as to lend 35 comfort and ease to the user, yet economical 40 in production.

With these and other objects in view which may be incident to my improvements, the invention consists in the parts and combinations to be hereinafter set forth and claimed, 45 with the understanding that the several necessary elements comprising my invention, may be varied in construction, proportions and arrangement, without departing from the spirit and scope of the appended claims.

50 In order to make my invention more clear-

ly understood, I have shown in the accompanying drawings means for carrying the same into practical effect, without limiting the improvements in their useful applications to the particular constructions, which 55 for the purpose of explanation, have been made the subject of illustration.

In the drawings forming a part of this specification:

Figure 1 is a side elevation of a boning 60 knife illustrating a shield for this character of knife applied,

Fig. 2 is a view illustrating the shield in front elevation,

Fig. 3 is a sectional view taken on line 3—3 65 Fig. 2,

Fig. 4 is a sectional view taken on line 4—4 Fig. 2 with the blade and handle in dotted lines,

Fig. 5 is a front elevation of a guard 70 employed in connection with various types of knives,

Fig. 6 is a sectional view taken on line 6—6 Fig. 5,

Fig. 7 is an elevation taken from the handle 75 side of a modified form of guard for general use,

Fig. 8 is a side elevation,

Fig. 9 is a bottom plan view,

Fig. 10 is an elevation taken from the 80 handle side illustrating a guard for general use,

Fig. 11 is a sectional view taken on line 11—11 Fig. 10,

Fig. 12 is an elevation taken from the 85 handle side, illustrating the form of shield used in connection with a butcher knife,

Fig. 13 is a sectional view taken on line 13—13 Fig. 12,

Fig. 14 is an elevation taken from the 90 handle end of the knife, illustrating a guard used in connection with a butcher knife,

Fig. 15 is a sectional view taken on line 15—15 Fig. 14,

Fig. 16 is a front elevation taken from the 95 blade end of the knife, illustrating a guard used in connection with a pork ribbing knife, and

Fig. 17 is a side elevation.

Referring by numerals to the drawings 1 100

represents the blade and 2 the handle of a knife commonly known as a boning knife. The handle is known as the diamond-shape handle, the general run of knives used in the meat packing industry being equipped with handles of this type.

Mounted upon the handle 2, is a guard 3 comprising a plate or shield oval in general contour being broader at the bottom 4 than at the top 5. Stamped or punched from the center of the shield 3 are corresponding and oppositely disposed flanges 6. In stamping the flanges 6 from the shield 3 there is formed in the shield an aperture 7 which conforms to the diamond-shape handle hereinabove referred to.

The guard thus formed is drawn over the knife blade and slipped on the forward end of the handle where it is secured by screws 8 or any other suitable fastening means.

The particular configuration of the shield 3 provides an area giving ample protection to the greater expanse of a clenched hand when holding the boning knife in the position required for operating purposes, and also affords protection to the finger section of a clenched hand.

The guard is stamped from a single piece of metal, thus it may be economically manufactured. It is strong and durable and susceptible of being easily and quickly removed or attached.

In Figures 5, 6, 7, 8, 9, 10, and 11, I have shown a modified form of guard designed for use in connection with various types of knives employed in the operations of butchering or cutting of meat or similar substances. In the construction of this form of guard I employ a plate 3 quasi-triangular in form having oppositely disposed wings 9 and a downwardly projecting lip 10 which is curved backward as indicated at 11, the object of which will hereinafter appear.

From between the wings 9 opposite the lip 10 is stamped and bent corresponding and oppositely disposed flanges 12, having apertures 13, the object of which will herein-after appear. In stamping and forming the flanges 12 there is produced a notch 14 shaped to fit snugly upon the forward end of a diamond-shape handle and to be detachably secured thereto by screws or other fastening means engaging the apertures 13.

In Figures 10 and 11 the means of securing the guard to the knife handle is somewhat modified. In lieu of the flanges 13 and the diamond-shaped notch 14, there is formed a circular aperture 15 having a collar 16 with a clamping bolt 17.

In each of these guards which are intended for general use it is to be noted that the oppositely disposed wings and the downwardly and backwardly projecting lip vary slightly in general contour. While these

guards are intended for general use, in meat boning operations a slight change is requisite, such change being accomplished by flattening out the curvature in the lip 10.

In these forms of guards which are intended for general use it is to be noted that the area between the wings 9 is adequate to accommodate the spread of the clenched hand when the knife handle is grasped in the full grip for operating purposes, thus effectively shielding and protecting the hand and preventing the hand from slipping from the handle to the blade and subsequent injury thereto. The lip 10 not only prevents the fingers from slipping forward on the blade but owing to the backward curve removes any interference between the guard and the product worked upon.

In Figures 12, 13, 14, and 15 I have shown guards particularly constructed for use in connection with a butcher's knife. The means of mounting the guard upon the handle is the same as that described and shown in Figure 1 to 5 inclusive. It is of course to be understood that the contour of the opening or aperture 7 may be varied to suit the particular formation of the forward end of any knife handle.

In each of these guards, I provide the plate 3 with oppositely disposed wings 9 and a downwardly projecting lip 10 which is curved backward as shown at 11. Above the aperture 6 in the top of the plate and in a line with the lip 10 is a depression 18 formed by swaging the metal in the opposite direction from the curvature 11 of the lip 10. The depression 18 is so formed as to give an easy and comfortable rest for the first joint of a thumb.

The flaring wings 9 accommodate and protect the spread of a clenched hand when the handle is grasped in the full grip for operating purposes and to effectively prevent the hand from slipping from the handle to the blade, thus preventing injury thereto.

The general contour of the plate 3 is such as to eliminate any sharp angles and to materially increase the structural strength. The downwardly backwardly projecting lip 10 serves to prevent the fingers from slipping to the blade and also serves to prevent any interference between the guard and the product worked upon.

In Figures 16 and 17 I have shown a further modification of my improved guard. This type of guard is particularly constructed for use in connection with a pork ribbing knife. The plate 3 is in the form of an irregular disk from the periphery of which is stamped and bent flanges 12 having apertures 13 by means of which the plate is secured to a handle. The angles formed by the stamping and bending of the flanges being rounded to avoid any sharp edges. The form of guard here shown is particularly

adapted to afford protection to the thumb and under finger arear of a clenched hand when grasping the handle of a pork ribbing knife in the position required for operating purposes. In such operations, it being requisite that the knuckle portion of the operating hand shall closely approach the animal carcass, and the taper of the blade causing the operating hand to form an angle of approximately 20 degrees with the animal carcass, the handle guard has been so designed that interference thereby with the operating process is overcome.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

Having thus described the various features of my invention what I claim as new and desire to secure by Letters Patent is:

1. A knife guard comprising, a plate having corresponding and oppositely disposed wings, a downwardly projecting lip, the end of the lip being curved backward, flanges formed integral with the body of the plate between the wings, an aperture formed centrally between the wings and demountable fastening means in the flanges.

2. A knife guard comprising a plate having corresponding and oppositely disposed wings, a downwardly backwardly projecting lip, a depression in the edge of the plate opposite the lip, flanges projecting from the center of the plate and an aperture between the flanges.

3. A knife guard comprising a plate having corresponding and oppositely disposed wings, a downwardly projecting lip, the end of the lip being curved backward, a depression in the edge of the plate opposite the lip, corresponding and oppositely disposed flanges projecting from the center of the plate, an aperture formed in the center of the plate, and demountable fastening means in the flanges.

4. A knife comprising a blade portion, a handle portion and a guard mounted on the handle portion, said guard comprising a plate having corresponding and oppositely disposed wings, a downwardly projecting lip, the end of the lip being curved backward, flanges formed integral with the body of the plate between the wings, an aperture formed centrally between the wings and demountable fastening means in the flanges.

5. A knife comprising a blade portion, a handle portion and a guard mounted on the handle portion, said guard comprising a plate having corresponding and oppositely

disposed wings, a downwardly backwardly projecting lip, a depression in the edge of the plate opposite the lip, flanges projecting from the center of the plate and an aperture between the flanges.

6. A knife comprising a blade portion, a handle portion and a guard mounted on the handle portion, said guard comprising a plate having corresponding and oppositely disposed wings, a downwardly projecting lip, the end of the lip being curved backward, a depression in the edge of the plate opposite the lip, corresponding and oppositely disposed flanges projecting from the center of the plate, an aperture formed in the center of the plate and demountable fastening means in the flanges.

In testimony whereof I affix my signature.

PRESTON D. CALLUM.
